S. RUTENBERG

NECKTIE AND LINING

Filed June 29, 1926

UNITED STATES PATENT OFFICE.

SAMUEL RUTENBERG, OF NEW YORK, N. Y.

NECKTIE AND LINING.

Application filed June 29, 1926. Serial No. 119,388.

This invention relates to an improved necktie and has for an object to provide an improved construction wherein most of the lining may be readily exposed for pressing.

Another object of the invention is to provide a necktie and lining wherein a reinforcing lining extends from near one end to the other and at the large or fore end of the tie an enclosing lining is superposed to present an extra thickness to the lining at that point.

A further object, more specifically is to provide in a necktie a lining wherein there is presented a tubular portion and a central flat stiffening portion with lines of stitching connecting these portions together.

In the accompanying drawings—

Figure 1 is a plan view of a necktie disclosing an embodiment of the invention with a portion broken away, better illustrating the construction;

Figure 2 is a sectional view through Figure 1 on the line 2—2, on a greatly enlarged scale;

Figure 3 is a sectional view through Figure 1 on the line 3—3, on a large scale;

Figure 4 is a sectional view through Figure 1 on the line 4—4, on a large scale;

Figure 5 is a plan view of the lining shown in Figure 1;

Figure 6 is an enlarged longitudinal sectional view through Figure 5 on the line 6—6;

Figure 7 is an enlarged view of the right hand end of the tie as shown in Figure 1 with part of the lining exposed.

Referring to the accompanying drawings by numerals, 1 indicates what may be termed the fore end of the tie, which is the large end, 2 a neck section and 3 is a small end or flap section. These parts are made substantially in the usual manner, except the arrangement of the lines of stitching 4 which extends on each side and each end of the neck section 2. These lines of stitching extend entirely through the necktie including a lining strip 5. It will be noted from Figures 5 and 6 that the lining strip 5 extends from point 6 to the end 7 and consequently reinforces the neck section 2 and part of the flap section 3. Connected to the

strip 5 and slightly overlapping the same at point 6 is a reinforcing section 8 secured to the section 5 by suitable lines of stitching 9 which also extend through a covering lining 10 which covers the strip 8. Strips 5 and 8 are preferably comparatively stiff, but may be made of any material, as for instance buckram or a desired grade of canvas.

The covering lining 10 is preferably of lighter material, as for instance, a light cotton goods. The overlapping edges of the covering lining 10 are connected by stitching 11 which extends through the strip 8, and the strip 8 and covering lining 10 are also connected together by the stitching 9. The outer end of the covering lining has the inturned ends stitched together by the line of stitching 12. In referring to the section 2 it will be noted, in Figure 3, that the strip 5 reinforces this section and in addition an outside reinforcing and sliding strip 13 is provided, the same being held in place by the lines of stitching 4, and it will also be noted that the tie is formed with a piece of cloth 14 folded so that the meeting edges will be substantially covered by a strip 13. From the neck section 2 to within a short distance of the respective ends of the tie, the edges of the body strip 14 are connected together by a suitable line of stitching 15 which is not exposed upon the reverse side of the tie but will be exposed when the tie is turned inside out.

The fore end of the body 14 of the tie is secured to the lining by the portion of the stitches 4 at the end of the neck section 2 and is unattached throughout the remainder of its length to the lining.

By providing the lining as shown in Figure 5 and connecting the fore end of the body of the tie to the same by lines of stitching 4 only, the fore end 1 may be telescoped or slipped back over the lining as indicated in Figure 7 or until the lining is exposed to the part carrying the stitching 9. This will permit anyone to press the lining independently of the body of the tie, and consequently will permit the body to be moved back and pressed properly on top of the lining.

What I claim is:

A necktie comprising a body having the edges of the fore end thereof permanently secured together to within a short distance of its end, and a lining for the fore end, said lining consisting of a strip of stiff material and a covering enclosing the same, the cov-

ering and strip being secured together and to the neck section of the tie, and the body of said fore end being secured to the lining 10 adjacent the neck section and unattached throughout the remainder of its length.

SAMUEL RUTENBERG.
